REMOTELY CONTROLLED SELF-PROPELLED
TOY

Frederick P. Schur, Chicago, Ill.

Application September 4, 1940, Serial No. 355,347

5 Claims. (Cl. 46—210)

This invention relates to remotely controlled self-propelled toys and its principal object is to provide a toy that is amusing, entertaining and interesting to children.

Another object is to provide an electric motor propelled vehicle with remote control means whereby its direction of travel can be controlled from a remote place.

Another object is to provide a remotely controlled self-propelled toy, of simple and comparatively inexpensive construction.

Another object is to provide a toy having electric motor operated propelling means and a remote control therefor, having an extension cord and plug which may be plugged into a wall socket so as to place the toy in service.

Other objects and advantages will appear in the course of this specification and with said objects and advantages in view, this invention consists in the several novel features hereinafter fully described and claimed.

The invention is clearly illustrated in the accompanying drawings in which:

Fig. 1 is a side elevation of a remotely controlled self-propelled toy, embodying one form of the invention, with certain electric conductors partly broken away.

Fig. 2 is a plan of the self-propelled element thereof with certain electric conductors shown in section.

Fig. 3 is a vertical longitudinal section through the body of the self-propelled element seen in Figs. 1 and 2, with the motors and other internal parts shown in side elevation.

Fig. 4 is an enlarged view of a portable switch unit, looking from below, with the cover of the casing thereof removed and part of the wiring omitted for the sake of clearness.

Fig. 5 is a vertical cross section taken on line 5—5 of Fig. 4, but showing the switch unit in 40 upright position.

Fig. 6 is a detail side elevation of certain members of the switch seen in Fig. 5, and

Fig. 7 is a diagrammatic view of the electric circuits employed for controlling the operation of the toy.

Referring to said drawings, which are merely illustrative of one embodiment of the invention, the reference character 10 designates a self-propelled vehicle here shown in the form of a miniature tank, comprising a hollow body 11, driving wheels 12, 13 and idler wheels 14, one driving wheel and a set of idler wheels being disposed on each side of the body, and having a traction belt or endless track 15 trained there-

around. Desirably a miniature turret 16 rises from the body, from which protrudes the muzzle of a miniature cannon 17 or other ordnance. Obviously the self-propelled vehicle may take various forms as desired, simulating various kinds of vehicles. The body 11 is preferably composed of light gauge sheet metal, providing a top, bottom, sides and ends.

The idler wheels are journaled on fixed shafts 18, 18a, which project beyond the sides of the body, but the driving wheels 12, 13 are rigidly mounted on shafts 19, 20, each mounted in and driven by a reversing electric motor 21 or 22, which is mounted on a frame comprising two bars 23 within the body 11 and bolted or otherwise secured to a cross bar 23a, which is fastened to two bars 23b, carried by the shafts 18a. The shafts 18 are secured to the side walls of the motors. There is one motor and its driving wheel at each end of the frame, with the driving wheels thereof disposed on the two sides of the body, whereby when both motors are rotating the driving wheels in one direction, the vehicle is driven forwards, and when the direction of rotation of the driving wheels is reversed, the vehicle is driven backwards. The direction of rotation of either motor and its driving wheel may be reversed, whereby the toy is caused to turn around, and by stopping the operation of one motor, the toy may be caused to travel along a curved line. Desirably each motor embodies speed reducing means for its drive shaft.

For controlling the direction of rotation of each motor from a remote place a portable electric switch unit 24 has been provided, which is connected to the motors of the vehicle by flexible electric conductors designated generally by 25, of suitable length as will be presently described.

The electric switch unit is desirably mounted in a casing or other container 26 (see Figs. 4 and 5) having a lid 27 removably secured on an open side thereof. Secured at one end of the casing is a main electric switch 28 interposed in one line 29 of an extension cord 30 of suitable length, having a plug 31 on its free end, which may be plugged into an ordinary wall socket (not shown) for putting the toy into service.

Secured within the casing 26 at its other end are two electric switches, 32, 33, each for controlling the circuits to a motor 21 or 22. For convenience in illustrating the invention the electric switches 32, 33 are shown as of the double throw, double pole type of switch, having shifting or sliding contacts 34a, 34b, 35a, 35b, se-

cured in slides, 34, 35, formed of non-conducting material and each having a button 34c or 35c which protrudes through a wall in the casing whereby it may be readily manipulated.

Each switch 32 or 33 (see Fig. 7) has six fixed poles or contacts, 36, 37, 38, 39, 40, 41, arranged in pairs and mounted in a base 42a which is formed of non-conducting material. In one position of the sliding contacts 34, 35 of each switch, they contact respectively with contacts 36, 38 and 37, 39, and in another position they contact with contacts 38, 40 and 39, 41. In an intermediate position the sliding contacts are out of contact with any two of the fixed contacts. Plates 34x, 35x, secured to a wall of the casing, and provided with fingers engaging the bases 42a, fasten the switches to the casing.

The contacts 36, 41 of each switch 32 or 33 are connected by a conductor 42, and contacts 37, 40 thereof are connected by a conductor 43, thereby providing a cross over from contact 36 to 41, and a cross over from 37 to 40 in each switch. Connecting the contacts 36, 37 of each switch with the motor, 21 or 22, it controls, are conductors 44, 45, and 44a, 45a, the conductors 44, 45 running to the brushes of motor 21, and the conductors 44a, 45a, running to the brushes of motor 22.

From the contact 38 of each switch 32 or 33 a conductor 46 or 46a runs to the field of motor 21 or 22, and from the field of motor 21 a conductor 47 runs back to the wire 29a of the extension cord 30. From the field of motor 22 a conductor 47c runs to conductor 41. The other wire 29 of the extension cord runs through the switch 28 to conductor 41a, which runs to contact 39 of switch 32. A conductor 47b runs from conductor 41a to contact 39 of switch 33.

The two motors 21, 22 are illustrated as reversed and set end to end in order to conserve space in the body, and as a consequence forward rotation of motor 21 drives its driving wheel 12 in the direction of the arrow thereon in Fig. 1, thereby propelling the vehicle in its forward direction. Inasmuch as forward rotation of motor 22 drives its driving wheel 13 in the reverse direction to that of driving wheel 12, switch 33 is connected with motor 22 in such manner that the direction of rotation of motor 22 is reversed to rotate its driving wheel 13 in the same direction as the driving wheel 12 so as to drive the vehicle forward, when both switches are set to drive the vehicle forward. For the purposes of illustration, switch 32 is set to drive the vehicle forward, and switch 33 is set to drive the vehicle backwards.

In accordance with this arrangement of motors, the conductor 45 runs from contact 37 of switch 32 to the upper brush of motor 21 and from the lower brush conductor 44 runs contact 36, whereas for motor 22 conductor 44a runs from contact 37 of switch 33 to the lower brush of motor 22 and conductor 45a runs from the upper brush thereof to contact 36.

For giving added attraction to the toy, it is preferred to provide an electric vibrating sounding device 48 in the toy for imparting staccato like sound, simulating the fire of rapid-fire arms. The sounding device 48 may be of any of the well known commercial types operating on alternating current, or it may be in the nature of an electric buzzer if desired, having an armature that strikes against a stationary part. The core of sound device 48 is connected by conductor 50, through a push button 51 secured in the switch casing, to

conductor 47a and by conductor 52 to the return conductor 47.

In the operation of the toy, the extension cord plug is plugged into an electric socket, and the switch 28 is closed. With the buttons 34c, 35c set in the position shown in full line in Fig. 1, the vehicle is driven forwards, and with the buttons set in the dotted line position, the vehicle is driven backwards. With one button in full line position and the other in dotted line position the vehicle will travel in a circle, and with one of the buttons in a neutral position, the vehicle will travel along a long curved line.

The circuits for controlling the direction of travel of the vehicle may be readily traced in Fig. 7 as follows: for motor 21 when propelling the vehicle forward, the circuit runs from the main line 29, through switch 28 and conductor 47a to contact 39 of switch 32, thence through shifting contact 34a to contact 37, and through conductor 45 to the upper brush of motor 21, then back from the lower brush thereof to contact 36; through shifting contact 34b to contact 38; through conductor 46 to the field of motor 21, and through conductor 47 back to the other line 29a of the extension cord.

For motor 22, with the contacts 35a, 35b of switch 33 set in the same position as contacts 34a, 34b of switch 32, the circuit is traced from conductor 47a, through conductor 47b to contact 39 of switch 33, and thence through the brushes and field of motor 22 as has been described in connection with motor 21, except that the conductor from contact 37 runs to the lower brush of motor 22 so that its direction of rotation is reversed as has been explained.

For propelling the vehicle backwards, both switches 32, 33 are set as shown for switch 33 in Fig. 7, thereby reversing the direction of the flow of current through the brushes. For motor 22 the circuit is traced from conductor 47b to contact 39 as before explained, thence through shifting contact 35a to contact 41; through conductor 42 to conductor 45a to the upper brush of motor 22, and from the lower brush thereof to conductor 43 and to contact 40, thence through shifting contact 35b to contact 38, through conductor 46a to the field of motor 22 and back through conductor 47c to the return conductor 47.

With the contacts of switch 32 set as shown in switch 33 the circuit for motor 21 is traced from conductor 47a to contact 39, then through shifting contact 34a to contact 41, through conductor 42 to contact 36 and through conductor 44 to the lower brush of motor 21, and back from the upper brush, through conductor 45 and conductor 43 to contact 40, then through shifting contact 34b to contact 38, through conductor 46 to the field of motor 21 and back through conductor 47 to line 29a of the extension cord. The direction of rotation of motor 21 is then reversed, thereby driving its drive wheel backwards, whereas the direction of rotation of motor 22 is forward, but because of its reversed position it drives its driving wheel backwards.

It will be understood that by shifting one button 34c or 35c forwards and one backwards, the shifting contacts will occupy the position shown in Fig. 7 or in the opposite positions, and one motor will drive its drive wheel forwards and the other will drive its drive wheel backwards, thereby causing the vehicle to travel in a circle. If one shifting contact is set in a neutral position, then only one motor will run, and thereby propel the vehicle in a long curve.

The circuit for the sounding device 48 is traced from the conductor 47a through button 51, conductor 50, the coil of the sounding device and through conductor 52 back to the return conductor 47.

By pressing the button 51 the circuit is closed through the coil of the sounding device, and the armature thereof is vibrated, causing a staccato like sound.

I claim as new and desire to secure by Letters Patent:

1. A remotely controlled self-propelled toy comprising a vehicle, propelling means therefor, including two reversing electric motors mounted in the vehicle, two driving wheels, one only located on each side of the vehicle, and each driven independently of the other by a motor, idler wheels on both sides of the vehicle, and traction belts, one trained around each driving wheel and its associated idler wheels, a remotely located portable switch casing, two double throw reversing switches mounted in said casing, two sets of flexible conductors, each connecting contacts of one switch with a motor whereby both motors are run forwards or backwards or either motor is run in a direction reversely with respect to the other in accordance with the setting of the switches, and an extension cord connected to contacts of both switches.

2. A remotely controlled self-propelled toy comprising a vehicle, propelling means therefor, including two reversing electric motors mounted in the vehicle, two driving wheels, one only located at one side of the vehicle adjacent one end thereof, and the other one located on the other side of the vehicle adjacent the other end thereof, and each driven independently of the other by a motor, idler wheels on both sides of the vehicle, and traction belts, one trained around each driving wheel and its associated idler wheels, a remotely located portable switch unit comprising two double throw, double pole electric reversing switches, and electric conductors for each motor, connecting poles of each switch with the brushes and field of the associated motor, whereby both motors may be run forwards or backwards, or may run in reverse directions with respect to each other, in accordance with the position of the movable contacts of the switch, a main line connected to a pole of each switch and a return line from the field of each motor.

3. A remotely controlled self-propelled toy comprising a body, two reversing electric motors therein, one at each end, a frame supporting said motors, shafts mounted in said frame, idler wheels on both ends of said shafts and supporting the body and motors, other idler wheels, one located on one side of the body at one end thereof and one located on the other side of the body at the other end thereof, shafts secured to the bodies of the motor and carrying said last mentioned idler wheels, two driving wheels, each disposed on a side of the body in

coaxial alignment with one of the last mentioned idler wheels, drive shafts for said driving wheels, each driven independently of the other by a motor, and traction belts, one trained around each driving wheel and its associated idler wheels, a remotely located portable switch unit comprising two double throw, double pole electric reversing switches, and electric conductors for each motor, connecting poles of each switch with the brushes and field of the associated motor, whereby both motors may be run forwards or backwards, or in reverse directions with respect to each other, in accordance with the position of the movable contacts of the switch, a main line connected to a pole of each switch and a return line from the field of each motor.

4. A remotely controlled self-propelled toy comprising a vehicle, two reversible electric motors mounted therein, two driving wheels, one only disposed on a side of the vehicle adjacent one end thereof, and the other one disposed on the other side of the vehicle adjacent the other end thereof, drive shafts, one for each driving wheel, and driven independently of the other by an adjacent motor, two idler wheels, each disposed on the sides of the vehicle opposite one of the driving wheels, shafts therefor, other idler wheels and shafts therefor for supporting the vehicle, two endless belts, each trained around a driving wheel and the idler wheels that are disposed on the same side of the vehicle as the driving wheel, two portable double throw double pole reversing switches, one for each motor, wiring connections between each switch and its associated motor, whereby either motor may run in a direction reversely of the other, in accordance with the setting of the switches, a main line running to each switch and a return line running from each motor, and an extension cord connected to the terminals of said main and return lines.

5. A remotely controlled self-propelled toy comprising a vehicle, propelling means therefor, including two reversing electric motors mounted in the vehicle, two drive shafts, one driven by each motor, one extending to one side of the vehicle and one extending to the other side thereof, two driving wheels, one mounted on each drive shaft, one at one side of the vehicle and one at the other side thereof, idler wheels aligned with said driving wheels, two traction belts trained over the driving wheels and idler wheels aligned therewith, separate electrical conductors for both motors, and two remotely located reversing switches, one for the electrical conductors of each motor, for separately controlling the direction of rotation of the motors, whereby both driving wheels may run forwards or backwards or the driving wheels may run in reverse directions with respect to each other in accordance with the setting of the switches, and the vehicle may thereby be run forwards or backwards or may be turned around.

FREDERICK P. SCHUR.
